UNITED STATES PATENT OFFICE.

ISIDORE BIRGÉ, OF PHILADELPHIA, PENNSYLVANIA, ASSIGNOR TO THE TRANSIT APPARATUS COMPANY, (LIMITED,) OF SAME PLACE.

STORE-SERVICE APPARATUS.

SPECIFICATION forming part of Letters Patent No. 325,382, dated September 1, 1885.

Application filed April 23, 1885. (No model.)

To all whom it may concern:

Be it known that I, ISIDORE BIRGÉ, a citizen of the United States, residing in the city and county of Philadelphia, in the State of Pennsylvania, have invented an Improvement 5 in Store-Service Apparatus, of which the following is a specification.

My invention relates in general to the class of store-service apparatus in which the traveling carrier is a basket or other goods-receiver suspended from the depending arm or hanger of a one or two wheeled truck the wheel or wheels of which travel upon an elevated track composed of a single rail.

15 Heretofore in the operation of traveling carriers of the above class the centrifugal force of the receiver and depending hanger has, as the truck has traveled upon curved portions of the track, tended to cause the 20 wheel or wheels to run at a tangent off the track, and so to displace the truck from the track. Heretofore, also, when a carrier-truck has become derailed there has been no provision of means to prevent its falling.

25 The object of my invention is to provide effective means for preventing any displacement of the carrier-truck from the track even upon curves of the shortest radius or of abruptly-varying direction, and also for preventing 30 a derailed truck from falling. These objects I attain by providing, in connection with curved portions of the track or carrying rail, a guard-rail supported at about the level of the track, between which and the track there 35 is space sufficient for the depending arm of a carrier to hang and travel freely, but which is so close to track that there is not room for a derailed carrier-truck to fall between them, and by also providing, in conjunction with 40 said curved portions, at a level below that of the track and to the outside of the curves, a lower guide or guard rail, which I term the "hanger-rail."

A track embodying my improvements is 45 represented in the accompanying drawings and described in this specification.

In the drawings, which represent a track conveniently embodying a good form of my improvements and a carrier thereupon, Figure 50 1 is an end partly sectional elevational view; Fig. 2, a top plan view; Fig. 3, a side eleva-

tion; Fig. 4, a diagrammatic plan illustrative of a guarded track having bends of opposite curvature; and Fig. 5 a view similar to Fig. 1, showing the action of the hanger-rail. 55

Similar letters of reference indicate corresponding parts.

In the drawings, A is a depending suspender or hanging arch-shaped bracket, which is a convenient device for supporting the track or 60 carrying rail B, the guard-rail, and the hanger-rail.

C is the wheel of a carrier-truck, D, from which is suspended a depending hanger or pendulous arm, E, which supports the basket 65 or goods-receiver.

F is a guard-rail, which is conveniently connected with and carried by the suspender A in a position which is preferably exactly abreast that of the track or carrying rail, but 70 which is placed so close to the track that there is not sufficient interspace for a carrier-truck to fall through. Both the carrying-rail and the guard-rail are, however, relatively suspended and supported at such a distance apart 75 that between them is a continuous opening, G, longitudinally extending and preferably co-extensive with the length of the curved portions of the track. Through this opening depends and travels the pendulous arm of the 80 truck, the oscillatory movement of which in either direction is, if desired, checked and controlled either, as the case may be, by the carrying-rail or by the guard-rail, which may be set so closely together as to subserve such 85 purpose.

Instead of being abreast the carrying-rail, the guard-rail might, to a certain extent, be either above or below it. The better construction, however, is that represented and described. The guard-rail is, as stated, 90 applied at curves, and is always applied upon the same relative side of the track or carrying rail, without regard to its being upon the inside or outside of curves, and this for the reason that were said guard-rail always, for 95 instance, placed upon the outside of every curve in tracks portions of which take on the form of reverse curves, it is manifest that the carrier-hanger would not be always between the two rails. Now, as it is an essential of this 100 feature of my invention that the guard-rail should always be so disposed that the hanger

or depending arm will pass between it and the carrying-rail, it is obvious that, as stated, said guard-rail, although not usually continuous throughout straight portions of the track, must 5 occupy always the same relative side of a given track at curved portions thereof, without regard to the varying curvature or given direction of said track.

H is what I term the "hanger-rail," conveniently supported by the bracket I, which is a part of or connected with the suspender A. This hanger-rail is applied at a proper distance below the carrying rail or track, and is invariably applied at the outside of every 15 curve and never at the inside, so that, according to the direction of the curve, the said hanger-rail is in line, or almost in line, below either the carrying-rail or the guard-rail, and this for the reason, as already explained, that 20 upon certain curves the guard-rail is to the outside of the track, while upon other curves the track is upon the outside of the guard-rail.

As the especial purpose of the hanger-rail 25 is to prevent such extreme outward or centrifugal throw of the depending arm or hanger of the truck as would have a tendency to unship the carrier wheel or wheels from the track, it is obvious that the said hanger rail 30 must be within range of any reasonable throw of the hanger, as illustrated in dotted lines in Fig. 1, and in practice I prefer to suspend it almost in line but a little to the outside below either the track or the guard-rail.

35 The diagrammatic plan of Fig. 4 illustrates the relative arrangement of the carrying-rail, guard-rail, and hanger-rail upon a track having a reverse curve. It is possible to employ the guard-rail without employing the hanger-rail, and to employ the hanger-rail without the guard-rail. The maximum of security 40 against both derailment and falling is, however, secured by employing both together. I do not, however, desire to limit myself to an 45 invariable conjoint employment of the two devices, as, in some instances, and with certain builds of carrier, one of the devices alone is an ample and sufficient security.

Having thus described my invention, I claim 50 and desire to secure by Letters Patent—

1. In combination with a single carrying rail or track for the wheeled carrier of a store-service apparatus, a guard-rail suspended or supported in propinquity to the track, and in

such manner as to leave a longitudinally-extending continuous and vertically free open space between said guard-rail and said track or carrying rail. 55

2. In a store-service apparatus, the combination of a suitably-supported carrying rail or track, a suitably-supported guard-rail in propinquity thereto, but so disposed as to leave a continuous open space between it and the carrying-rail, a traveling wheeled carrier adapted to run upon the carrying-rail and 60 provided with a depending or pendulous arm or hanger, which passes down through and travels within the open space between the guard-rail and carrying-rail, substantially as and for the purpose set forth. 65

3. In combination with a single carrying rail or track for the wheeled carrier of a store-service apparatus, a hanger-rail suspended or supported below said carrying-rail at the outside 70 side of curved portions thereof. 75

4. In a store-service apparatus, the combination of a carrying rail or track for a wheeled carrier, a hanger-rail suspended or supported below said carrying-rail at the outside of curved portions thereof, and a traveling 80 wheeled carrier adapted to run upon the carrying-rail, and provided with a depending or pendulous arm or hanger, the arrangement being such that the centrifugal throw of the hanger is limited by the hanger-rail. 85

5. In a store-service apparatus, the combination of a curved track composed of a single suitably suspended or supported carrying-rail, a guard-rail adjacent to a given side of said track at curved portions thereof, but at 90 such distance from said track as to leave a continuous open space between them, a hanger-rail suitably suspended or supported below the level of the track or guard rail and to the outside of all curves, and a traveling wheeled 95 carrier the wheel or wheels of which run upon the track and which is provided with a depending arm adapted at curved portions of the track to travel between the track and the guard-rail and to the inside of the hanger-rail, substantially as shown and described, 100 and for the purposes set forth.

In testimony whereof I have hereunto signed my name this 28th day of March, A. D. 1885.

ISIDORE BIRGÉ.

In presence of—

J. BONSALL TAYLOR,
WM. C. STRAWBRIDGE.
